UNITED STATES PATENT OFFICE

JOSEPH GOMBAR, OF DETROIT, MICHIGAN
DAVENPORT

REISSUED

Application filed April 19, 1926. Serial No. 102,923.

My invention relates to new and useful improvement in a davenport, and has for its object the provision of a davenport which may be, when folded outwardly into operative position, used as a bed.

It is an object of the present invention to provide a structure permitting of this dual use and provided with supports automatically adjustable to operative or inoperative position depending upon the use to which the davenport is put.

Another object of the invention is the provision of a structure of this class which when swung to position for use as a bed will afford a rigid and durable structure.

Another object of the invention is the provision of a plurality of collapsible end folding parts adapted to automatically move into their folded position upon swinging of one part of the davenport into a certain position.

Another object of the invention is the provision on the bed of end supports adapted for affording abutments when the device is used as a bed and for serving to retain the mattress and bed clothes in position when the device is being folded into position for use as a davenport.

Other objects will appear hereinafter.

The invention consists in the combination and arrangement of parts hereinafter described and claimed.

The invention will be best understood from a reference to the accompanying drawings which form a part of this specification and in which,

Fig. 1 is a perspective view of the invention in its outwardly folded position.

Fig. 2 is a side elevational view of the invention showing it applied to a davenport in its collapsing position.

Fig. 3 is an end elevational view of the invention in its outwardly moved position showing it applied to a davenport.

Fig. 4 is a fragmentary top plan view taken on substantially line 4-4 of Fig. 3.

Fig. 5 is a fragmentary side elevational view of a supporting member which is mounted on the davenport frame.

The invention is adapted for use with a davenport having an upholstered back 8 and

side arms 9. The invention comprises a frame having at opposite sides cross members 11 connected by side rails 12 and 13. The construction at each side of the davenport is similar so that a description of one side only is given herein. Pivotedly connected at one end to the cross member 11 at 14' and projecting upwardly therefrom is a support 14. Pivotedly connected at one end to the cross member 11 at 15' and projecting upwardly therefrom is a support 15. Connected to the cross member 11 and braced by the brace 17 is an upright support 16, a spring 18 serving to connect the support 15 with the brace 17. Projecting upwardly from the cross member 11 is a support 20 upon which is mounted a strap 20' having a plate 21 secured thereto. A brace 144 serves to connect the cross member 11, the support 14 and the plate 21 to reinforce and retain these parts rigid. Projecting outwardly from the strap 20' are spaced studs 22', each of which is provided with an enlarged head 22 spaced from the strap 20'. Secured to the frame of the davenport proper (this frame of the davenport not being shown in as much as it in itself forms no specific part of this invention and may be of any well known structure) is a strap of metal 23 having elongated slots 24 formed therein and communicating at one end with an enlargement 25, the arrangement being such that the head may be projected through the enlarged portion 25 and thence moved downwardly so that the studs 22' are in engagement, when in the slots 24 thus serving to lock the frame of the invention securely upon the frame of the davenport with which used. A U-shaped frame having legs 26 and a bight 27 is formed from angle-iron or other suitable material and pivotedly connected at one end to the link 29 at 29', the opposite end of said link being pivotedly connected to a side rail 30 of the frame embodying the rails 30, 31, 33 and 34. As shown in Fig. 1 the rails 30 and 34 are each connected to the rail 31 by the diagonally extending brace 32.

Pivotedly connected at one end to the rail 31 in spaced relation are supporting legs 35 to each of which is pivotally connected at 36

one end an operating arm 36, the other end of said arm 36 being pivotally connected to one of the legs of the U-shaped bracket 37, the other leg of which is pivotally connected to an arm 38. Connecting the rail 30 to the seat frame 40 are legs 50, an angle iron 51 being secured to the undersurface of the seat frame 40. The frame 40 may be termed an auxiliary frame. Connected to the angle iron 51 pivotally is one end of an arm 41 which at its opposite end is pivotally connected to the rail 30 at 142. Pivotally connected intermediate its ends at 142 to the rail 30 is one end of an arm 42, the other end of which is pivotally connected at 44 to an arm 43, this arm 43 being pivotally connected to the link 29 at 45 and provided at its end with an angularly turned portion 46 which engages in a notch 48 formed in the support 14, this arm 43 being projected through a slot 47 formed in the link 29. The arms 41 and 43 cooperate together and function as a toggle.

As shown clearly in Fig. 4 the arm 42 is also projected through a slot 42' formed in the rail 30.

Connected to the rail 30 and projecting upwardly therefrom are supports 54 and 55, each of which is provided at its upper end with an angularly turned tongue 54' and 55' respectively for limiting the swinging movement of U-shaped abutment 52 which is pivotally connected at the ends of its legs to the supports 54 and 55.

As shown in the drawings a spring 56 is used to retain this abutment in upright position.

When the device is used as a davenport it is folded into the position shown in Fig. 2 and when it is desired to use the device as a bed it is folded into the position shown in Fig. 1, suitable springs 28 being connected to the rails and cross-members as shown in the drawings.

When the device is in the position shown in Fig. 1 the U-shaped abutments 52 are raised into upwardly projected position so as to serve the obvious purpose.

Preliminarily to folding the device upon its axis abutments are folded inwardly toward each other so as to serve as a retaining member for the mattress, bed clothes, and the like.

As the device is folded inwardly a certain distance the angularly turned portion 46 will disengage from the notch 48, thus permitting the arms 42 and 43 to move into the position shown in Fig. 2. The support 14 in this movement will rock sufficiently to permit the engagement of the angularly turned portion 46 of the arm 43 to engage in the notch 48 so as to lock the device in the position shown in full lines in Fig. 3. When it is desired to collapse the structure and move it into the form shown in Fig. 2, the support 14 may be

tilted against the tension of the spring 19. In Fig. 2 and in Fig. 1 I have shown the device as partly folded over in dotted lines to indicate the operation of the various parts. The arm 38 serves, upon movement of the frame having the rail 31 a predetermined distance, to rock the U-shaped member 37 on its pivot. This rocking will serve to rock the legs 35 on their pivot inwardly toward each other so as to fold them into parallel relation to the arm 31. Similarly when the device is unfolded a certain distance this U-shaped member will be rocked in the opposite direction to move the legs 35 into vertical relation to the rail 31 so as to form the necessary supports.

While I have illustrated and described the precise form of structure I do not wish to limit myself to the precise form of structure shown but desire to avail myself of such variation and modifications as come within the scope of the appended claims.

Having thus described my invention what I claim as new and desire to secure by Letters Patent is:

1. A davenport of the class described comprising: a supporting frame; a frame having means by which it is swingably mounted on said supporting frame and adapted in one position for folding over said supporting frame and lying above it and in another position for forming an extension on said supporting frame; a link pivoted to the swingable frame and adapted to swing from a vertical depending position to a position in horizontal alignment with the extended swingable frame; a support projecting upwardly from the lower part of the supporting frame and provided with a notch near its upper end; a toggle comprising two links pivoted together and pivoted at one end on the swingable frame and at its other end on the link and provided with means engaging the notch when the link and frame are horizontally aligned whereby the link is supported and locked in horizontal position.

2. A davenport of the class described comprising: a supporting frame; a frame having means by which it is swingably mounted on said supporting frame and adapted in one position for folding over said supporting frame and lying above it and in another position for forming an extension on said supporting frame; a support projected upwardly from the lower end of said supporting frame and provided with a notch in its upper end; a toggle connected at one end to said swingably mounted frame and engageable in one position for engaging in said notch and locking said swingably mounted frame against swingable movement; a supporting leg pivoted to said swingably mounted frame and adapted for swinging from operative to inoperative positions; a U-shaped member; means by which the U-shaped member is

pivots mounted on the swingable frame; an operating arm pivotally connected at one end to the supporting leg and at the other to one leg of the U-shaped member, a second arm pivotally connected at one end to the other leg of the U-shaped member and at the other to an extension of one of the toggle links whereby rocking of said toggle incident to swinging the sections effects swinging of the leg from one position to another and a seat section connected to the extremity of said toggle extension.

In testimony whereof I have signed the foregoing.

JOSEPH GOMBAR.
